[57] **CLAIM**

The ornamental design for a reconfigurable robotic humanoid toy assembly, as shown and described.

DESCRIPTION

FIG. 1 is a front side perspective view of a reconfigurable robotic humanoid toy assembly showing my new design;

FIG. 2 is a front elevational view thereof;

FIG. 3 is a right side elevational view thereof;

FIG. 4 is a left side elevational view thereof;

FIG. 5 is a rear side elevational view thereof;

FIG. 6 is a top plan view thereof;

FIG. 7 is a bottom plan view thereof;

FIG. 8 is a front side perspective view of the toy being reconfigured into city playset in a battle station mode;

FIG. 9 is a front side perspective view of the toy reconfigured into city playset in a battle station mode;

FIG. 10 is a perspective view of the toy being reconfigured into city playset in a basic city form; and

FIG. 11 is a front side perspective view of the toy reconfigured into city playset in a basic city mode.

FIG. 1

FIG. 2

FIG. 3

FIG. 4

FIG. 5

FIG. 6

FIG. 7

FIG. 8

FIG. 9

FIG.10

FIG.11
